GARMENT HANGER SUPPORT FOR A SHOWER HEAD

Gerhard Kollitz, 1301 E. Commonwealth Ave., Apt. 111,
Fullerton, Calif. 92631

Filed Jan. 28, 1974, Ser. No. 437,753

Term of patent 14 years

Int. Cl. D6—06

U.S. CL. D6—86

FIG. 1 is a perspective view of a first embodiment of a garment hanger support for a shower head showing my new design;

FIG. 2 is a left side elevation view thereof;

FIG. 3 is a rear elevation view thereof;

FIG. 4 is a perspective view of a modified form of the garment hanger support for a shower head shown in FIG. 1;

FIG. 5 is a left side elevation view thereof; and

FIG. 6 is a rear elevation view thereof.

I claim:

The ornamental design for a garment hanger support for a shower head, as shown and described.
